UNITED STATES PATENT OFFICE.

HOWARD L. MOULE, OF ROCK CREEK, WYOMING TERRITORY.

ATTACHMENT FOR ANCHORS.

SPECIFICATION forming part of Letters Patent No. 427,347, dated May 6, 1890.

Application filed August 27, 1889. Serial No. 322,081. (No model.)

To all whom it may concern:

Be it known that I, HOWARD L. MOULE, of Rock Creek, in the county of Albany and Territory of Wyoming, have invented a new 5 and Improved Attachment for Anchors, of which the following is a full, clear, and exact description.

My invention relates to an improved attachment for anchors, and has for its object 10 to provide a means whereby anchors of ordinary form, which are too light for efficient service, may be readily and cheaply increased in weight at a point where it will be most available to render the anchor reliable in use.

15 With this object in view my invention consists in the provision of a clamping gravity-block, which is secured in place so as to embrace the crown and shank of the anchor, whereby the weight of the crown-piece will 20 be so increased as to insure the embedding of the flukes and proper retention of the anchor.

Reference is to be had to the accompanying drawings, forming a part of this specification, in which similar letters of reference indicate 25 corresponding parts in all the figures.

Figure 1 is a side view of an anchor in position for use, showing my improvement secured thereon. Fig. 2 is an edge view of the same, partly in section, on the line *x x* in 30 Fig. 1. Fig. 3 is a plan view of the anchor, partly in section, on the line *y y* in Fig. 2; and Fig. 4 is an enlarged view of a portion of the improvement detached from the anchor.

The ordinary form of anchor is preferred 35 for general use on account of its simplicity and peculiarity of form, which latter adapts it to hold firmly when in use and be snugly as well as securely "stowed" when hoisted to place at the side of the vessel's bow.

40 It is necessary for the proper operation of an anchor that its weight and spread of flukes be proportioned to the capacity of the vessel it is to hold.

Owing to the oxidation due to exposure of 45 anchors alternately to water and the atmosphere, their weight is considerably reduced after service for a term of years, and they become too light for the safe anchoring of the craft they held reliably when they were of 50 full weight.

To compensate for reduction of weight, or in other cases to render a light anchor avail-

able to hold a vessel of greater tonnage than it was originally designed for, I have provided the clamping-blocks B B. These blocks 55 are constructed of cast metal, and as the two pieces are duplicates a description of one will suffice for both. As will be seen in Fig. 4, the half-section B is recessed at B' B², thus adapting the piece to conform to one-half the 60 thickness of the anchor-shank A and crown portion C. The standing portions B³ and their rounded front ends *d*, respectively, hug the opposite sides of the shank A, and fit against the juncture of the shank and crown when in 65 position, as indicated in Fig. 3, where both sections are shown in secured adjustment upon the anchor.

The form of the gravity-block is not important, but that shown is preferred, as it 70 affords weight properly disposed and in compact shape, this being the main essential to be provided.

The duplicate sections B B, as shown in Fig. 2, embrace the shank A, as well as the 75 crown, and are slightly separated to permit a clamping action of the pieces upon the parts mentioned. A suitable number of bolts F are inserted through transverse holes made in the pieces or sections B B, which bolts have 80 conical heads *b* and squared nuts *c* seated in recesses provided in the sections, so that by a proper manipulation of the nuts the sections will be firmly secured in position, and no improper projections extend beyond the 85 general surface of the sections to catch the cable or foul the anchor with other ropes or chains when it is being hoisted or cast overboard.

By the provision of the gravity-block just 90 described any light anchor, if otherwise strong enough, may be given the weight necessary to embed its flukes and retain them so engaged, which will prevent dragging of the anchor in an obvious manner.

Having thus described my invention, what I claim as new, and desire to secure by Letters Patent, is—

1. An attachment for anchors, consisting of two recessed sections which embrace and are 100 secured on the shank and crown of the anchor, substantially as set forth.

2. An attachment for anchors, consisting of two equal recessed half-sections clamped upon

the shank and crown of the anchor, substantially as set forth.

3. In a gravity-block attachment for an anchor, the combination, with the mating recessed half-sections of a weight which embrace the crown and shank of an anchor, of a securing device which retains the parts

clamped on an anchor, substantially as set forth.

HOWARD L. MOULE.
